UNITED STATES PATENT OFFICE.

EDWARD B. HESS, OF BROOKLYN, NEW YORK.

WIND-SHIELD FOR AUTOMOBILES.

1,244,732.

Specification of Letters Patent. Patented Oct. 30, 1917.

Application filed October 12, 1916. Serial No. 125,182.

To all whom it may concern:

Be it known that I, EDWARD B. HESS, a citizen of the United States, residing at Brooklyn, in the county of Kings and State 5 of New York, have invented certain new and useful Improvements in Wind-Shields for Automobiles, of which the following is a specification.

This invention relates particularly to wind 10 shields for automobiles of the general kind shown in my U. S. Patent No. 1,178,319, of April 4, 1916, in which a three-part shield is shown comprising a main lower section adapted to be fixed in a vertical plane be- 15 low the line of vision or to be swung in- ward for purposes of ventilation, an upper section mounted to swing outward to a position above the direct line of vision or to be held in a vertical plane above the main lower 20 section, and a third or auxiliary section so mounted as to stand at times vertically parallel with and close to the main lower section or to be moved upward into the direct line of vision below the upper section when the 25 latter is extended to serve as a rain guard.

In many automobiles the steering wheel is located quite close to the wind shield and it is not possible to elevate and depress an auxiliary section of the kind shown in my for- 30 mer patent when it is directly pivoted at its upper end to the wind shield frame or standards.

The primary object of my present invention is to provide means whereby the auxiliary section may be conveniently raised and lowered in such manner as to clear the steering wheel and whereby said shield section may be securely held in its adjusted positions.

40 In carrying out my invention I provide standards which support the three shield sections, the upper section being pivotally connected at its upper end to the upper portions of the standards and the main lower section 45 being pivotally connected at its upper end with the middle portions of the standards. The auxiliary section is carried by parallel links of such length and so shaped as to at times support the auxiliary section in a plane 50 close to and parallel with the main lower section and at other times in a plane above the lower section within the direct line of vision and below the extended upper section.

My improvements are shown in the accompanying drawings, in which:

55 Figure 1 is a view showing in side elevation a part of the front portion of an automobile and in vertical section my improved wind shield. In this figure of the drawings the upper section is extended forward while the auxiliary section is lowered being parallel with and close to the main lower section in a plane below the direct line of vision.

60 Fig. 2 is a view similar to Fig. 1 but with the auxiliary section partially raised, and this figure of the drawing indicates how the auxiliary section clears the steering wheel while being raised.

65 Fig. 3 is a detail view showing a device which may be employed for pivotally connecting the wind shield sections with the standards and for holding them in their adjusted positions.

70 Fig. 4 is a detail view showing devices for pivotally connecting the shield sections to the standards and for locking them and also additional devices which may be employed for holding or locking the shield sections when adjusted.

75 Fig. 5 is a detail view showing in side elevation two of the links employed for supporting the auxiliary section, the links being disposed in the position they assume when the auxiliary section is lowered.

80 Fig. 6 is a view similar to Fig. 1 but showing the main lower section closed, the upper section extended, and the auxiliary section raised and located above the main lower section and below the extended upper section.

85 Fig. 7 is a view similar to Fig. 6 but showing how the main lower section may be moved inward for purposes of ventilation.

90 Fig. 8 is a detail view of the links as they appear when the auxiliary shield section is raised.

95 A part of the hood or casing of an automobile is indicated at A and the wind shield is located in rear thereof. Standards B rise from the automobile body or casing on opposite sides thereof and are rigidly fixed thereto. The three shield sections C, D and E are supported by the standards preferably in the manner shown.

100 The upper shield section C is pivotally connected near its upper end with the upper ends of the standards in the manner in-

dicated at *c* by suitable devices which serve as pivots and also serve to lock the shield in its adjusted positions. I may also employ devices *c'* for locking the upper shield section when lowered. The upper shield section is so mounted that it may hang in a vertical plane in the direct line of vision when the auxiliary section is lowered, as indicated in Fig. 1, and when in this position it 10 may be held firmly in place by the locking devices before described, or the upper section may be extended in the manner indicated and held at any desired inclination.

The main lower shield section *D* is pivotally connected at its upper end to the standards *B* by devices *d* of the kind shown in Fig. 3, which also serve to lock or hold said lower section in any desired position. The main lower section may be held in a vertical 20 plane below the line of vision as indicated in Figs. 2 and 6, or it may be swung inward for purposes of ventilation, as shown in Fig. 7, and so held by the devices *d*.

The auxiliary section *E* is preferably 25 made of somewhat smaller dimensions than the companion lower section *D*, and it is carried by parallel links *F*, *F'*, four of such links being preferably employed. The links it will be observed are bent at their ends *f*, *f'*. The bent ends *f* of the upper links *F* are pivotally connected with the standards *B*, preferably by the same devices *d* that pivot the lower section to the standards. The section *E* it will be observed is arranged on the 35 inside of the lower section and the ends *f* of the links *F* extend inward from the standards. The outer ends of the upper links *F* are pivoted to the auxiliary section at *e* about midway between its lower and upper 40 ends. The bent ends *f'* of the lower links are pivoted to the lower end or lower portion of the auxiliary section at *e'*, while the inner ends of these lower links are pivotally connected with the standards some distance below the pivots *d* of the upper links. The 45 links are all of substantially the same length and operate as parallel links and thus serve to hold the auxiliary section in a vertical position whatever be its adjustment.

50 When the auxiliary section is in its lowermost position (Fig. 1) it is held by the links close to the main lower section and may be locked by the devices *d*. When it is desired to raise the auxiliary section the 55 devices *d* are loosened and the auxiliary section is drawn inward and at the same time it moves upward (Fig. 2) clearing the steering wheel and always retaining a vertical condition. When the upper section is ex- 60 tended and the auxiliary section is raised to its full extent (Fig. 6) it may be locked by the devices *c'*. At this time the wind shield

is closed and the upper section serves as a protection or guard for the auxiliary section, preventing rain, snow or dust from 65 driving against it or lodging on it.

It will be observed that while the upper links *F* have their bent ends pivoted to the standards, the bent ends *f'* of the lower links are pivoted to the auxiliary section and thus 70 when said section is raised to its full extent (Fig. 6) the bent ends of the links interlock as shown in Fig. 8, thus serving to prevent the auxiliary section from moving forward to an undue extent. 75

It will be further observed that the links are so pivoted to the standards that when the auxiliary section is either raised or depressed the links are for the most part 80 enclosed between the standards and the frames of the shield sections and are thus for the most part hidden or concealed.

A wind shield constructed in accordance with my invention is very simple, can be cheaply manufactured and is capable of varied 85 adjustments to suit varying conditions.

I claim as my invention:

1. A wind shield comprising shield-supporting standards, an upper shield section pivoted at its upper end to the upper ends 90 of the standards, a main lower shield section pivoted to the standards, an auxiliary section, and parallel links pivotally connected with the auxiliary section and pivotally connected with the standards in approximately the same vertical plane as the 95 main lower section.

2. A wind shield comprising shield-supporting standards, an upper shield section pivoted at its upper end to the upper ends 100 of the standards, a main lower shield section pivoted to the standards, an auxiliary section, and upper and lower parallel links having bent ends, the upper links having their bent ends pivoted to the standards and 105 the lower links having their bent ends pivoted to the auxiliary section.

3. A wind shield comprising shield-supporting standards, a lower shield section mounted therein, an auxiliary section, upper parallel links having bent ends pivoted to the standards and pivoted to the auxiliary section between its upper and lower ends, and lower parallel links having bent ends pivotally connected with the lower portion of the auxiliary section and pivotally connected with the standards, said links being of such length that when the auxiliary section is raised the bent ends of the links interlock. 110 115 120

In testimony whereof, I have hereunto subscribed my name.

EDWARD B. HESS.
